UNITED STATES PATENT OFFICE

MORRIS BROOKS, OF EAST ORANGE, NEW JERSEY, AND JOHN CARNER, OF NEW YORK, N. Y.

DESIGN FOR AN ACCORDION CASE OR THE LIKE

Application filed June 13, 1931. Serial No. 40,208. Term of patent 14 years.

To all whom it may concern:

Be it known that we, MORRIS BROOKS and JOHN CARNER, citizens of the United States, and residents of East Orange, Essex County, New Jersey, and New York, in the county of Kings and State of New York, respectively, have invented a new, original, and ornamental Design for Accordion Cases or the like, of which the following is a specification, reference being had to the accompanying drawings, forming part thereof.

We claim:

The ornamental design for an accordion case or the like, as shown.

MORRIS BROOKS.
JOHN CARNER.
